CAMPING DEVICE

Wilbur M. Weisz and Edwin H. Royse,
Dallas, Tex.

Application July 23, 1942, Serial No. 451,990

10 Claims. (Cl. 5—112)

This invention relates to new and useful improvements in camping devices.

One object of the invention is to provide an improved device which is arranged to form a cot or hammock for sleeping purposes and which is readily collapsible whereby, when not in use, it may be folded into a comparatively small compact unit so as to be easily portable.

An important object of the invention is to provide an improved device which is adapted for use in camping outdoors and which not only forms a sleeping cot or hammock but also provides a weatherproof shelter or small tent, which makes the device practical for use in various climates.

A particular object of the invention is to provide an improved camping device, of the character described, wherein spaced end members are adapted to suspend a hammock or body support therebetween and in a position above the ground level, whereby the hammock is free from transverse supports therebeneath and a comfortable bed is provided.

Another object of the invention is to provide an improved camping device, wherein the end members each comprise a tripod which is readily collapsible, said tripods being arranged to be enclosed by end flaps and the entire structure being adapted to be covered by a removable cover, whereby a small tent is formed; the removable cover also acting as an outside casing or enclosure for the various parts of the device when said parts are collapsed or disassembled.

A further object of the invention is to provide a camping device, of the character, wherein the various connections between the parts are made by dowels or similar removable means and also wherein the end supports or members are capable of an adjustment to compensate for stretch of the hammock or body support, whereby said hammock may be properly positioned at all times.

Still another object of the invention is to provide a device, of the character, having the hammock or body support formed with a depending skirt therearound, which skirt is of sufficient length to reach the ground so that a dead air space may be had beneath the hammock to insulate the interior of the device against cold.

A construction designed to carry out the invention will be hereinafter described together with other features of the invention.

The invention will be more readily understood from a reading of the following specification and by reference to the accompanying drawings, wherein an example of the invention is shown, and wherein:

Figure 1 is an isometric view of the end supports of the device, the canvas portions of said device being omitted.

Figure 2 is a side elevation of the device, constructed in accordance with the invention and having the outer cover removed therefrom,

Figure 3 is a reduced side elevation of the complete device, with the outside cover in position thereon,

Figure 4 is a longitudinal, cross-sectional view, taken on the line 4—4 of Figure 2,

Figure 5 is a horizontal cross-sectional view taken on the line 5—5 of Figure 2,

Figure 6 is a partial transverse vertical sectional view, taken on the line 6—6 of Figure 4,

Figure 7 is a partial, transverse vertical sectional view, taken on the line 7—7 of Figure 4,

Figure 8 is a transverse, sectional view illustrating the joint between the base members and taken on the line 8—8 of Figure 1,

Figure 9 is an isometric view of the hammock or body support of the device, which support is constructed of canvas or other similar material,

Figure 10 is a transverse sectional view taken on the line 10—10 of Figure 9,

Figure 11 is a transverse sectional view taken on the line 11—11 of Figure 9,

Figure 12 is a partial isometric view showing one end of the outside cover of the device,

Figure 13 is an enlarged sectional view of the pivoted joint between the three rods of one of the end supports, said rods being illustrated in their spread position, and

Figure 14 is a view similar to Figure 13, with the rods in a folded or collapsed position.

In the drawings, the letter A designates an end support which consists of a trio of rods 10, 11 and 12. The rods have their upper ends connected to each other by means of a flexible connecting member 13 (Figures 13 and 14). The member 13 may be a leather thong and extends through openings 14 which are formed in the rods, the ends of the member 13 being provided with heads 15 which are preferably constructed

of metal and which prevent said member from pulling through the openings 14. Manifestly, the flexible member 13 permits a pivoting and hinging of the various rods 10, 11 and 12 with respect to each other and said rods may be spread outwardly, as shown in Figure 1 or may be collapsed inwardly toward each other so as to lie in parallel relation, as shown in Figure 14. Although a flexible connection such as 13 has been found suitable, any desired flexible joint may be employed.

The rods 10, 11 and 12 are adapted to be spread

to form a tripod, with the hinge joint at the apex thereof. The lower ends of the three rods are mounted upon base elements 16 and 17 which elements are shown in the form of wooden bars. The bar 17 is disposed at a right angle to the bar 16 and is connected to the central portion of the former by a tongue 18 which engages within a groove 19 formed in the bar 16. The rod 10 has its lower end formed with an inclined dowel pin 20 which is engageable within an inclined recess 21 in the upper surface of the bar 17 (Figure 7).

The rods 11 and 12 are provided with similar dowel pins 22 on their lower ends which fit within recesses 23 provided at the outer ends of the bar 16. It is manifest that the rods may be easily disconnected from the bars 16 and 17 and said rods folded in parallel relation so as to occupy a minimum amount of space. Also, the bars 16 and 17 may be disconnected from each other and the length of these bars is substantially the same as the length of the rods 10, 11 and 12 whereby all of the parts may be placed in adjacent parallel relation so as to be readily portable.

A second end support B which is constructed in exactly the same manner as the support A is provided and is spaced from the first support, as is clearly shown in Figure 1. A hammock C preferably of canvas or other similar material is adapted to be suspended between and within the end supports A and B. As is clearly shown in Figure 9, the hammock has its ends tapered or formed of a general triangular shape as indicated at 24, whereby these ends will fit within the tripods formed by the rods of the end supports A and B. A plurality of openings 25 are formed in the edge portions of the hammock and the rods 11 and 12 of the end supports A and B are adapted to pass through these openings. Each opening has a strap 26 which is formed integral with the hammock around its outer edge and this strap engages the rods 11 and 12, being secured to said rods by rivets 27 or other fastening means.

The ends of the hammock are formed with recesses 25a which receive the rods 10 of the end supports and tabs 26a having snap fasteners 27a arranged to removably secure the ends of the hammock to the rods 10. Thus, the hammock is permanently affixed to the rods 11 and 12 and removably secured to the rods 10 of the end supports and this arrangement facilitates collapse and folding of the unit, as will be explained.

As is clearly shown in Figure 2, the hammock C is secured to the rods at a point above the lower ends thereof, whereby the hammock is suspended in spaced relation to the ground. When the hammock is secured to the supports A and B and the weight of a person is placed thereon, said hammock will tend to pull the rods 10, 11 and 12 inwardly toward each other and due to the dowel pin connections between said rods and the base bars 16 and 17, a rigid support for the hammock is had and danger of collapse of the tripod is obviated.

As explained, the hammock C may be formed of any suitable material and also may be constructed in any desired manner. It is preferable, however, to reinforce the edge or marginal portion of said hammock by sewing a reinforcing cord 28 therein (Figures 10 and 11). In addition, the central portion of the hammock C may be reinforced by wooden rods 29 which extend between the rods 11 and 12 of the units A and B, the rods 29 being inserted within sleeves 30

which are formed integral with the material of the hammock by merely folding the material around the rod and sewing the same to the under side of the hammock, as is clearly shown in Figure 10. Each rod 29 has its end formed with a dowel pin 31 which is adapted to engage a recess 32 in the rods 11 and 12 of the end supports A and B and in this manner, the longitudinal edges of the hammock C between the end supports are suitably braced and reinforced.

The hammock C is preferably provided with a depending skirt 33 which has its upper end sewed or otherwise secured to the edge portions of said hammock. The skirt is of a sufficient length to permit its lower end to lie upon the ground, that is, the skirt is longer than the space between the hammock and the ground level. The skirt functions to create a dead air space below or beneath the hammock and in extremely cold climates, this dead air space provides an insulation to maintain the interior of the structure above the hammock substantially warm. Of course, when the device is used in warmer climates, the skirt 33 may be entirely eliminated.

For closing the space between the rods 10, 11 and 12 of the end supports so as to enclose the end portions of the hammock and to weather-proof the device, triangular flaps 34 and 35 are provided. These flaps may be formed as separate pieces but it is preferable that they be attached to, and form a part of, the hammock C. The flaps 34 are of a size to cover the space between the rods 10 and 11, while the flaps 35 are adapted to cover the opposite space between the rods 10 and 12. The flaps 34 are formed with tabs 36 having suitable fasteners 37 and as is clearly shown in Figure 2, said flaps are swung upwardly and the tabs are fastened around the rods 10 and 11. After each flap 34 is in position, the opposite flap 35 is swung upwardly to cover the space between the rods 10 and 12 and tabs 36a which are formed on one vertical edge of said flaps 35 are secured around the rod 12, being fastened by the fasteners 37a. The opposite vertical edge of each flap 35 is formed with an elongate strip 38 which is arranged to overlap the flap 34 along the rod 10, said strip being secured to said flap 34 by suitable snap fasteners 39. Obviously, when the flaps 34 and 35 are in position secured to the rods, the spaces between said rods are covered so that the head and foot portions of the hammock are protected against the weather.

For enclosing the entire interior of the structure after the flaps 34 and 35 have been secured in place, an outside cover 40 is provided. As is clearly shown in Figures 3 and 12, this cover extends between the end supports and is formed with end extensions 41 which engage over the apex of each tripod, each extension being suitably secured to the strip 38 by a suitable fastener 42. The sides of the cover 40 overhang the sides of the structure and also overlap the flaps 34 and 35. For fastening the lower portions of the sides of the cover 40 in place, suitable draw strings 43 are secured to the cover at each end thereof and each draw string 43 is threaded through a sleeve 44 formed in the lower edge of each side of the cover (Figure 12), the inner ends of said draw strings extending into the interior of the structure. After the cover 40 is in place, the occupant may enter the structure and then fasten the ends of the draw strings 43 to the rods 11 and 12 of the end support, such fastening being possible from

the interior. Obviously, when the cover 40 is in place, a weatherproof tent is had.

The entire structure is simple in construction and inexpensive to manufacture. The two tripods may be readily set up and the hammock is suspended therefrom. Since there are no cross or transverse braces beneath the hammock, a much more comfortable bed is provided because obviously, the flexible material of which the hammock is made will readily conform to the body of the occupant. The flaps 34 and 35 may be secured to the sides of the rods of the end supports or in warmer climates, these flaps may be omitted so as to provide sufficient ventilation. The skirt 33 which creates a dead air space beneath the hammock may or may not be employed, as desired. Also, the outside cover 40 may be used in colder climates and to protect the occupant from rain or other adverse weather. If desired, the cover 40, as well as the flaps 34 and 35, may be omitted and a mosquito netting substituted therefor, whereby the device is adaptable for use in tropical climates.

The device may be readily disassembled by first removing the outer cover 40 and releasing the flaps 34 and 35 from the rods. Disassembly may continue by disconnecting the reinforcing rods 29 from the rods 11 and 12, then disconnecting the rods 10, 11 and 12 from the base bars 16 and 17, and finally separating the bars 16 and 17 from each other. The ends of the hammock are then disengaged from the rods 10 of the end supports by unfastening the fasteners 27a. The rods of each end support are then swung inwardly toward each other to a collapsed position, such collapse being possible because of the triangular portions 24 of the hammock merely fold to permit the inward movement of the bars 11 and 12. The rods 10, 11 and 12, as well as the base bars 16 and 17 are then placed longitudinally on the central portion of the hammock and this positioning of the rods folds the triangular ends 24 of the hammock over the central portion thereof. The entire collapsed unit may then be rolled into the cover 40 which provides an outer casing or enclosure for the various disassembled parts. The roll so formed may be tied together by the draw strings 43 of the outside cover 40 and thus, the entire unit takes up a minimum amount of space and is readily portable.

The foregoing description of the invention is explanatory thereof and various changes in the size, shape and materials, as well as in the details of the illustrated construction may be made, within the scope of the appended claims, without departing from the spirit of the invention.

What we claim and desire to secure by Letters Patent is:

1. A camping device including, a pair of spaced end supports, each support comprising a trio of rods having their upper ends hinged together, whereby said rods may be spread to form a tripod, base members to which the lower ends of said rods are removably fastened, a hammock extending between the tripods and having its ends shaped to fit within the rods forming said tripods, and means for securing the peripheral portions of the hammock to the rods at a point spaced above the lower end of the rods, whereby the hammock is suspended from the end supports.

2. A camping device as set forth in claim 1, together with longitudinally extending reinforcing rods mounted in the marginal edge portions of the hammock, and means for removably fastening the ends of said rods to the end supports.

3. A camping device as set forth in claim 1, with flaps secured to the hammock and foldable upwardly over the rods of the end supports to cover said supports and to enclose the end portions of the hammock.

4. A camping device as set forth in claim 1, with a peripheral skirt secured to the hammock and depending downwardly therefrom to completely enclose the space beneath the hammock.

5. A camping device including, a pair of spaced end supports, each support including a plurality of rods having their upper ends hinged together, whereby the lower ends of the rods may be spread apart to form the support, means connecting and spacing the supports from each other, and a hammock extending between the supports and having its marginal edge portions secured to the means and said rods adjacent and spaced above the lower ends of the rods, whereby the hammock is rigidly suspended from the end supports and swinging of the same is prevented.

6. A camping device as set forth in claim 5 wherein the connecting and spacing means consist of longitudinally extending reinforcing members mounted in the marginal edge portions of the hammock, the ends of the members being removably fastened to the end supports.

7. A camping device as set forth in claim 5, together with flaps connected to the hammock and foldable upwardly over the rods of the end supports to cover said supports and to enclose the end portions of said hammock.

8. A camping device as set forth in claim 5, together with a peripheral skirt connected to the hammock and depending downwardly therefrom to the ground so as to completely enclose the space beneath said hammock and provide a dead-air space therebelow.

9. A camping device including, a pair of end supports, each support comprising a pair of base members disposed at a right angle to each other with the end of one member abutting the central portion of the other, means for removably securing the base members together, a trio of rods

50 having their upper ends hinged together with their lower ends removably secured to the base members, means for connecting and spacing said end supports from each other, a hammock extending between the end supports, and means 55 for removably securing the peripheral edge portions of the hammock to the connecting and spacing means and the rods adjacent and spaced above the lower ends thereof, whereby said hammock is rigidly suspended from said supports and side-sway of the same is prevented.

10. A camping device as set forth in claim 5, together with end flaps formed on the hammock adapted to cover the end supports to enclose the end portions of said hammock, an outer 65 cover overlying the hammock, and means for removably fastening the cover in position.

WILBUR M. WEISZ.
